UNITED STATES PATENT OFFICE.

MARCUS RUTHENBURG, OF LOCKPORT, NEW YORK.

FURNACE.

980,345.

Specification of Letters Patent. Patented Jan. 3, 1911.

Application filed November 9, 1907. Serial No. 461,518.

To all whom it may concern:

Be it known that I, MARCUS RUTHENBURG, of Lockport, in the county of Niagara and State of New York, have invented a certain 5 new and useful Improvement in Furnaces, whereof the following is a specification, reference being had to the accompanying drawings.

My improvement may be advantageously 10 employed in an electric furnace comprising a stationary casing in which the electrodes are mounted, and it is the object of my invention to provide a removable hearth arranged to form a floor for the furnace casing and comprising a receptacle in which molten material may be received and transported from said furnace.

As hereinafter described, said hearth is 15 circular, saucer shaped, and so constructed and arranged that it may be raised into operative relation with the furnace casing or lowered upon tracks on which it may be shifted laterally so as to be tilted and emptied into a suitable conveyer.

As hereinafter described, a vertical plunger 20 is arranged beneath the furnace to raise and lower said hearth, and the latter is provided with supporting wheels upon which it may be progressed when lowered.

A convenient adjunctive feature of the 25 invention is an auxiliary supporting device adapted to maintain the hearth in raised position independently of said plunger and comprising wedge blocks which are interposed between said tracks and wheels.

My invention comprises the various novel 30 features of construction and arrangement hereinafter more definitely specified and claimed.

In the drawings; Figure I, is a sectional view of a furnace showing a hearth raised into its normal operative relation with the furnace. Fig. II, is a view similar to Fig. I, but showing the hearth removed from the 35 furnace and tilted to discharge its contents into a conveyer. Fig. III, is a fragmentary sectional view taken on the line III, III, in Fig. I, showing an auxiliary supporting device in operative relation with one of the 40 supporting wheels of the hearth.

In said figures; the stationary furnace casing 1, is supported by the columns 2, above the track 3, and incloses the electrodes 5 and 6, which may be supported, raised and lowered therein by any convenient means. Said 45 furnace casing 1, is conveniently made cir-

cular, and, the removable hearths 8, are also circular and saucer shaped to form receptacles 9 for the molten material received from said casing. Said hearths are preferably formed of refractory material fitted in metallic casings 10, which, as shown, may be formed of two metallic shells disposed in concentric relation. Each hearth 8, is provided with a truck frame 12 and four supporting wheels 13 which register with said tracks 3; so that it may be progressed thereon to and from said casing 1.

The plunger 15, is arranged to reciprocate beneath said furnace casing 1, to raise and 50 lower said hearths, and may be conveniently actuated by hydraulic pressure in the cylinder 16; or be upheld by the detent 17, as shown in Fig. I.

A hearth 8, may be upheld in operative 55 relation with the casing 1, as shown in Fig. I, independently of said plunger 15, by auxiliary supporting devices comprising oppositely inclined wedges 18, having eyes 19, engaged by hook bars 20; the latter being 60 screw threaded and coupled by the turn buckle 21, so that the latter may be rotated to draw said wedges toward each other between said tracks 3 and wheels 13. When it is desired to discharge the contents of a 65 hearth, said turn buckle 21 may be reversely rotated to thrust said wedge blocks 18 apart, and, said blocks being removed while the hearth is supported by the plunger 15, the latter may be lowered until the hearth is 70 supported by the wheels 13 on the tracks 3. The hearth may then be shifted on said tracks until the wheels 13 encounter an abutment 22 which is local to said tracks, as 75 shown in Fig. II, and, thereupon, the hearth 80 may be tilted upon the pivotal support afforded by the axle 24, conveniently by the chain 25, engaging the clevis 26, on the 80 hearth shell 10, so as to discharge the contents of the hearth into a suitable conveyer, 85 for instance, a tang 28, mounted on a truck frame 29, provided with wheels 30 to traverse the tracks 31.

It is to be understood that a plurality of 90 hearths may be successively employed with the single furnace casing 1, shown in the drawings, for instance, said casing may be located between two similar conveyers into 95 which the contents of the hearths may be alternately emptied.

I do not desire to limit myself to the precise details of construction herein set forth,

as it is obvious that various modifications may be made therein without departing from the essential features of my invention as defined in the appended claims.

5. I claim:

1. In a furnace, the combination with a stationary casing; of a removable hearth for said casing; supporting wheels in operative relation with said hearth; a track arranged to engage said wheels when said hearth is lowered; and, means arranged to support said hearth in raised position, comprising oppositely inclined wedge blocks interposed between said wheels and track.
- 10 2. In a furnace, the combination with a stationary casing; of a removable hearth arranged to form a floor for said casing and comprising a receptacle for molten material; and, adjustable means arranged to support said hearth in operative relation with said casing, comprising a wedge.
- 15 3. In a furnace, the combination with a stationary casing; of a removable hearth arranged to form a floor for said casing and comprising a receptacle for molten material; adjustable means arranged to support said hearth in operative relation with said casing, comprising oppositely inclined wedges; and, means arranged to relatively shift said
- 20 30 4. In a furnace, the combination with a stationary casing; of a removable hearth arranged to form a floor for said casing and comprising a receptacle for molten material; means arranged to raise and lower said hearth with respect to said casing; and means distinct from said raising and lowering means and independent of said casing arranged to support said hearth in operative relation with said casing.
- 25 35 40 5. In a furnace, the combination with a

stationary casing; of a removable hearth arranged to form a floor for said casing and comprising a receptacle for molten material; means arranged to raise and lower said hearth with respect to said casing; and means independent of said casing, below said hearth and removable with respect to said raising and lowering means arranged to support said hearth in operative relation with said casing.

6. An electric furnace comprising a stationary casing; an electrode supported in a chamber in said casing; a removable hearth forming a floor in said casing; means arranged to raise and lower said hearth with respect to said electrode; and, means independent of said casing, below said hearth and removable with respect to said raising and lowering means, capable of retaining said hearth in operative relation with said casing.

7. In a furnace, the combination with a stationary casing; of a removable hearth arranged to form a floor for said casing, comprising a receptacle for molten material and having supporting wheels whereby it may be progressed to and from said casing; means arranged to raise and lower said hearth with respect to said casing; and means distinct from said raising and lowering means, extending below said supporting wheels and arranged to support said hearth in operative relation with said casing.

In testimony whereof, I have hereunto signed my name at London, England, this 22nd day of October, 1907.

MARCUS RUTHENBURG.

F. L. RAND.

Correction in Letters Patent No. 980,345.

It is hereby certified that in Letters Patent No. 980,345, granted January 3, 1911, upon the application of Marcus Ruthenburg, of Lockport, New York, for an improvement in "Furnaces," an error appears in the printed specification requiring correction as follows: Page 1, line 101, the word "tang" should read *tank*; and that the said Letters Patent should be read with this correction therein that the same may conform to the record of the case in the Patent Office.

Signed and sealed this 31st day of January, A. D., 1911.

[SEAL.]

C. C. BILLINGS,
Acting Commissioner of Patents.
